AUTOGRAPHIC REGISTER

Walter E. Oliver, Somerville, Mass.

Application November 13, 1935, Serial No. 49,468

1 Claim. (Cl. 282—12)

This invention relates to autographic registers, and the object is to provide a particularly simple and yet efficient mechanism of this nature for dispensing sections from so-called "packs" comprising a number of webs folded back and forth in zigzag form wherein effective registration of the superposed sections of the webs about to be inscribed is effected.

My invention will be well understood by reference to the following description taken in connection with the accompanying drawings of illustrative embodiments thereof, wherein:

Fig. 1 is a plan view of a so-called hand-pull register with parts broken away;

Fig. 2 is a central longitudinal section with parts shown in dotted lines in a displaced position;

Figs. 3, 4 and 5 are similar sections showing successive positions of the webs;

Fig. 6 is a longitudinal section of a register with mechanical feed; and

Figs. 7 and 8 are enlarged detail sections.

The cross-sectional views, Figs. 2 to 6, inclusive, are partly diagrammatic in their showing of the paper webs, as will be hereinafter more fully explained.

I believe that my invention will be most readily understood if I first describe didactically the particular mechanical construction of the embodiment thereof shown in Figs. 1 to 5 of the drawings, and thereafter by tracing the operation thereof in use the principles exemplified thereby will become apparent.

Referring particularly to Figs. 1 and 2 of the drawings, the register comprises a body 8 of box-like form with an open top. Herein a partition 10 within the body opposing an end wall 12 thereof defines a container which loosely receives the pack P from which the webs are dispensed. For simplicity the pack is herein shown to consist of the two webs A and B folded back and forth in zigzag form conveniently along lines of perforations which divide the webs into sections which are usually printed forms, each being a sales slip, a receipt or some other form of "ticket".

Obviously more than two webs may be used as is customary in the art. To show the webs in the cross-sectional views, Figs. 2 through 6, by cross-hatched area with the necessary exaggeration of the thickness would, I believe, lead to confusion and I have therefore indicated them as single lines in these figures and have shown them somewhat spaced from each other instead of in contact. These figures are therefore to be understood as diagrammatic to this extent and also

for clearness I have omitted therefrom the carbon paper C, presently to be referred to.

Hinged to pins 14 at the right-hand end of the body is a cover-like member, best seen in Fig. 2 in dotted lines, having flanges 16 which fit over the sides of the body and connecting webs 18 and 20, the former providing when the cover is in the closed-down position shown in full lines in Fig. 2 a table on which the tickets to be inscribed are disposed for writing upon while the part 20 may serve as a hand rest. The webs pass over the table beneath the overhanging guides 22 at either end thereof and may be confined laterally by the horizontal flanges 24 on angular members pivoted at 26 to the left-hand ends of the flanges 16 and adapted to be held folded in substantial alignment therewith by catches 28 (Fig. 1) on the sides of the body 8. The parts described may be swung upwardly above the pins 14 to permit the pack to be inserted in its container and the flanges 24 may be swung upwardly away from the table 18 in the manner indicated in Fig. 2 to facilitate initially threading the ends of the sections in position over the writing table 18.

As seen in Fig. 1, a compartment 29 may be formed at one side of the body to receive a roll of carbon paper C, a portion of which is drawn out over the table and interposed between the portions of the webs which lie thereon in well known manner.

Adjacent the feeding-in end of the table 18 in the closed position of the parts I have provided a curvilinear guide 30 of substantial radius about which the paper webs are drawn as they pass from the pack to the writing position. This guide herein takes the form of a roll journaled in the left-hand ends of the flanges 16. The statement that the guide or roll 30 is of substantial radius will later be more clearly understood from the explanation of the operation of the register. For the present I may say by way of example that in the case of a hand-pull register for dispensing tickets about $5\frac{3}{4}$ inches long and $4\frac{1}{2}$ inches wide I have had good results from a roll $\frac{1}{4}$ of an inch in diameter. The roll 30 in the closed position of the parts has substantial clearance from the adjacent end wall 12 of the register so that an unobstructed space is provided at the left of the roll for purposes which will appear. The webs are so led to the roll that they make a substantial arc of contact therewith, and for this purpose I preferably use a similar guide or roll 32 mounted adjacent the opposite end of the table approximately a ticket's length 55

away. Thus the arc of contact of the paper with the roll 30 is substantially a semi-circle in the example shown.

To permit the sections of the tickets which are overlying the table and have just been inscribed, such as the sections I in Fig. 2, to be grasped by the fingers to be withdrawn, bringing the succeeding sections II into position for inscription, the right-hand end of the table may be depressed at 34 and the end of the tickets are here supported, or even guided somewhat upwardly, by means of the spaced guides 36, perhaps best seen in Fig. 1, defining a space between them in which the edge of the tickets are exposed to be grasped between the thumb and finger, while the edge of the support 20 may be cut away at 38 to facilitate grasping of the ticket ends.

At one side of the path of the webs at the feeding-out end of the table 18 a short blade 40 projects upwardly thereon. When a set of tickets which have just been inscribed have been drawn out from over the table to permit a fresh set of tickets to be disposed thereon in writing position, they will have been carried in an upwardly trending direction passing above this blade until the line of perforation or fold between the tickets just inscribed in the new set is in alignment with the blade. The extending portions of the webs may be moved downwardly to cause the blade to break or cut the end of the line of perforation facilitating the tearing off of the inscribed tickets along this line. The action will be well understood by reference to Fig. 1 in which the tear has been shown as begun by the blade 40 and propagated for a short distance along the line of perforations.

Assuming a set of tickets to have been torn off in this manner, it will be seen that the tickets I in Fig 2 are disposed with the fold line *f* which connects them with the next set of tickets II located at the guide 30. The radius of this guide or roll is sufficiently large so that it will not catch in the manner of a sharp edge in the angle 45 of the fold. The actual size may vary, particularly as the angle of contact of the webs may be varied, but is such that the natural resilience of the end portions of the webs, which, if tightly tensioned, would be drawn down against the arc, 50 as in Fig. 7, will effectively under the conditions of tension present in a register spring out substantially to the position of the tangents, as shown in Fig. 8 and at the left of Fig. 1, the paper "breaking" freely at the hinge line formed by the 55 line of fold initially given in the pack.

Assuming the parts to be in the position of Fig. 2, if I grasp the ends of the set of tickets I and draw them toward the right in that figure, a substantial resistance will first be encountered 60 as the upwardly and leftwardly flaring and resiliently acting end portion of the tickets II is drawn down into contact with the curved surface of the roll. This corresponds to a movement from the position of Fig. 8 to the position of Fig. 7, in which latter figure the arrow is intended 65 to indicate that the webs are under draft. The resistance will be felt until the fold line passes to and beyond the position of Figs. 7 and 3 and the adjacent ends of the tickets I and II are disposed in a common plane. The tickets may then 70 be easily drawn forward until the succeeding fold line *f* passes over the arc of contact of roll 30. An increased resistance will then be noted because the tickets II and III have folded along 75 their line of connection and the forward edge

portions of tickets III tend to assume a position similar to Fig. 8 and act like a spring tending to draw backwardly on the tickets II and they are curved to the radius of the roll as in Fig. 7 only by an increased tension exercised by the hand on 5 the tickets II which are drawn forwardly. At this time also the fold line between the tickets I and II approaches the tearing off blade 40, giving a visual signal as well. The tickets II are drawn slightly beyond the position of Fig. 3, 10 that is, to the position of Fig. 7 in which the upwardly and leftwardly flaring end portions of the left-hand ends of tickets III are brought in contact with the arc of the roll under corresponding tension. The said tickets I may then 15 be torn off by striking the fold line against the blade 40 in the manner already described. This releases the tension on the tickets II, which are drawn back to the position of Figs. 4 and 8 by the spring of the ends of tickets III and are 20 realigned by the nesting of the fold lines in the original accurate register in which they were brought in the manufacture of the pack.

In a previous portion of the specification I have pointed out that the roll 30 had substantial clearance from the end wall 12 of the register, being unobstructed at the left-hand side, viewing Figs. 2 and 3. This, it will now be understood, is to permit the end portions to function in the manner described, springing to the tangential positions shown in Figs. 2, 4 and 8. The wall 12, however, may be so positioned that the resilient reaction of the end portion of the set of tickets just below the table serves, when the tension on the set of tickets above the table is released, to 30 throw the fold line over against the inner side of wall 12 which serves in the manner of an alignment gage.

It will be understood that in the initial manufacture of a pack of the kind shown the various sets of tickets are in accurate register. In dispensing the same, whether by hand or by mechanical means, disalignment within a single ticket's length is usually negligible but may be cumulative. By the present invention the set of tickets which is drawn over the table ready for inscription is permitted, as it were, to jog itself up into accurate register with respect to the fold line at their following ends, and this is effected each time a ticket is dispensed, doing away with 40 cumulative error. The action may be demonstrated in practice in a hand-pull register of the type illustrated in Figs. 1 to 5 by pulling off without opportunity for readjustment and without tearing off successive sets of tickets a number 45 of tickets in succession. The cumulative error will usually then be such as to be beyond the readjustment possibilities provided by the construction shown.

I have described the action of the webs at the roll 30. This action is preferably reinforced at the guide roll 32. As seen in Fig. 3, for example, not only are the leading ends of tickets II acting as a spring at roll 30, but also the leading ends 50 of tickets III are similarly disposed in a tangential position serving as a spring tending to draw rearwardly on the tickets II extending between the two rolls. I have previously stated that the rolls 30 and 32 were substantially a ticket's length apart. More accurately the arrangement 55 is such as to dispose a resiliently acting length of paper at the extremities of a ticket's length at opposite sides of the guides beyond the common tangent joining them. For a specific example I have found that in the case of guides disposed 70

substantially as shown and a quarter of an inch in diameter the horizontal distance between the center lines may advantageously be about $\frac{1}{16}$ of an inch less than a ticket's length.

With the parts in the position of Fig. 2, the tickets III have also raised the left-hand ends of the tickets IV providing an additional retarding spring which manifests itself in the resistance of the tickets to draft. This springiness is effective as the tickets pass through the position of Fig. 3, but substantially disappears as the tickets IV assume the rolled-up position of Fig. 4. The resistance to draft in moving to or from the position of Fig. 2 is therefore somewhat greater than that in moving to or from the position of Fig. 4, depending on whether the tickets are being dispensed from one end of the zigzag folded pack or the other. The provision of springing resistances both at the guide 30 and at the cooperating guide 32, however, provides an adequate re-adjusting force and a sufficient signal to the operator at all times. Also in passing from the position of Fig. 4 to the position of Fig. 2 the web IV passes from the looped-up position of Fig. 4 through the position of Fig. 5. As the loop shown in Fig. 4 disappears, rolling up and drawing out the tickets IV to the fold line at the right-hand of the pack, the last portion thereof will spring outwardly to the position shown in Fig. 1 until the force is balanced by the lifting and tensioning of the ends of tickets VI as shown at the left in Fig. 5. In the operation of the register this movement of the ends of the tickets from the position of Fig. 4 to the position of Fig. 5 is very noticeable to the person operating the register and is even audible and serves as an additional signal to proceed carefully since the fold line between III and IV is approaching the guide 30 and the increased tension due to the wrapping of the leading ends of tickets IV about that guide, which is the signal that the dispensing operation has been completed, will soon be felt.

In Fig. 6 I have shown a register operating on the same principles and having a mechanical feed. The position of the web in Fig. 6 corresponds to a position slightly subsequent to that of Fig. 3, but in this instance represents the position of rest of the tickets for inscription, this being due to the mechanical feed arrangement. The construction of the register may be generally similar to that of the hand-pull register, and in Fig. 6 I have used three-digit numbers of which the last two digits are the same as those of the corresponding parts in Figs. 1 to 5. Thus the register may have a body 108 in which the pack P is received and from which it is dispensed over rollers 134 and 130 of substantial radius to a table 118. To feed the webs I provide a roll 142 adapted to be turned by a hand crank 144. A releasable stop 146, not illustrated in detail but of a type well known in the art, permits the crank to be released from the position of Fig. 6 for a single revolution when it will again engage the stop. The roll 142 is an active surface or tread 148 projecting through an opening in the table 118 to the plane of the paper which is gripped between the same and a spring-pressed roller 150 geared to rotate with roll 142 at the same surface speed. The tread or active surface of the roll 148 is the same length as the length of the ticket but is gapped or broken. It may be assumed that an inscribed set of tickets has been drawn out and torn off

against the ledger blade 152 formed at the right-hand side of the housing for roll 150. The fold lines between successive sets of tickets are indicated by the letter f, and the tread 148 and the roll 150 are in contact firmly holding the heads 5 of the tickets both for the purpose that they shall not be displaced when the preceding set is torn off and to aid in positioning them during the writing operation. If now the stop 146 is released and the crank 144 turned clockwise, 10 viewing Fig. 6, the tread 148 will feed the tickets until the gap shown in the figure in approximately four o'clock position reaches twelve o'clock position opposite roll 150, at which time the feeding will be intermittent. The parts are so timed that 15 that fold line f which in Fig. 6 appears directly beneath the table 118 has then reached the roll 130. Consequently when the draft of the feed roll is thus intermittent, the ends of the tickets under the table will be permitted to spring out to 20 a tangential position relatively to the fold lines to the position of Fig. 2 or Fig. 4, jogging up and registering the portions of the webs which extend outwardly over the table and which are then free from restraint. As the rotation of the crank continues and the gap passes the twelve o'clock position, the tread will again engage the tickets and give them an additional feeding movement to bring the fold line underneath the tearing off blade 152. This additional feeding movement 25 may be very short and any disarrangement of register which might be effected therein will be negligible. On each operation of the register the sets of tickets are realigned and no cumulative error is possible. 35

I am aware that the invention may be embodied in other specific forms without departing from the spirit or essential attributes thereof, and I therefore desire the present embodiment to be considered in all respects as illustrative and not 40 restrictive; reference being had to the appended claim rather than to the foregoing description to indicate the scope of the invention.

I claim:

An autographic register for dispensing for inscription thereon successive sections of webs transversely folded in zigzag along predetermined, equally spaced lines to form a pack comprising a container for the pack, a table over which a section is disposed for inscription, a guide 45 adjacent an end of the table around which the webs are drawn from the pack having a curved surface of substantial radius, and means for maintaining the webs in contact therewith over an arc of such extent that a length of paper substantially equal to the tangents thereto exhibits 50 substantial resilience comprising a guide having a similarly curved surface about which the paper is looped, the guides being so spaced that, when a section of the webs is disposed over the table for inscription, a succeeding section will extend tangentially from the lower side of the first guide to the upper side of the second guide with end portions of the section projecting beyond the lines 55 of tangency, which end portions are of a length 60 to exhibit such substantial resilience that, when they with similar portions of adjacent sections are drawn by feeding traction of the webs against the arcs of the surfaces of the guides, they will, 65 on release of the feeding tension, assume positions substantially tangent thereto. 70

WALTER E. OLIVER.
